Patented Feb. 19, 1924.

UNITED STATES PATENT OFFICE.

ERNEST VON HAMBACH, OF CHICAGO, ILLINOIS, ASSIGNOR TO HERBERT D. LAFFERTY,
OF OAKLAND, CALIFORNIA.

TIMER.

Application filed March 28, 1921. Serial No. 456,461.

To all whom it may concern:

Be it known that I, ERNEST VON HAMBACH, a citizen of the United States of America, and resident of Chicago, Cook County, Illinois, have invented a certain new and useful Improvement in Timers, of which the following is a specification.

My invention relates to an improvement in timers and has for its object the provision of an efficient and economical structure which is particularly adapted for use on Ford cars.

Among the features and objects of my invention are the provisions of a timer having a casing of insulating material in which are mounted stationary brush holders carrying brushes which engage with a revolving contact.

Other features and objects of my invention will be more readily understood by having reference to the accompanying drawings in which I have illustrated one embodiment of my invention.

Fig. 1 is an end elevation looking into the timer casing.

Fig. 2 is a plan sectional view partly in elevation.

Fig. 3 is a detail sectional view showing the outer end of the casing and an engaging member for holding the timer in place.

I have illustrated the timer as mounted upon the end of a shaft 5 which is usually the cam shaft of the engine. This shaft is provided with a reduced portion 6 and a threaded end 7. Mounted upon the reduced end portion 6, there is a metallic sleeve 8 which carries upon its outer periphery a sleeve 9 of insulating material. The outer ends of these sleeves 8 and 9 are beveled or inclined, as clearly indicated in Fig. 2, to permit easy and ready assembly. Threaded upon the end 7 of the shaft 5 is a nut 10 which engages with the metallic sleeve 8, thus holding this sleeve on the shaft. Extending through the insulating sleeve 9 and metallic sleeve 8 is a metallic contact 11 which is preferably threaded through the metallic sleeve 8 so as to engage with the shaft 5 which is usually grounded. In order to prevent rotation of the sleeve 8 with respect to the cam shaft 5, and in order to properly position this sleeve on this shaft so that the contact 11 will be in proper timed relation with the movement of the cam shaft, there is provided in the sleeve 8 a lon-

gitudinal slot 12 within which the head of a pin 13 engages, this pin being set within a cylindrical hole in the cam shaft. Mounted so as to engage with the revolving contact 11 are a plurality of stationary brush contacts 14 which are mounted in metallic brush holders 15, being spring-pressed against the surface of the insulating sleeve or drum 9 by the springs 16. Each of these brush-holders consist of a hollow cylindrical section in which the brush contact is mounted and a stem 17 which projects through the insulating casing 18, being held in place by the nut 19. A suitable binding nut 20 likewise is mounted upon this stem 17 so as to permit the electrical connection to be made with this stem.

The insulating casing is preferably molded out of insulating material, such as bakelite, or some other hard insulating material. In order to permit the casing to be readily drawn from the mold, it is necessary that the mouth of the casing be flared, that is the inner and outer walls of the cylindrical portion 21 of this casing are inclined, as clearly indicated in Fig. 2. This inclination allows of sufficient "draw" to permit ready removal of the casing from the mold. In order that the brush-holders may be held in proper alignment in a plane at right angles to the axis of the cam shaft, it is necessary that adjacent the base of these brush-holders the casing be provided with a section having a flat inner surface which is parallel to the axis of the cam shaft as clearly indicated at 22 in Fig. 2. Likewise, adjacent each brush-holder there is provided on the exterior of the casing a boss 23 which is provided with a flat face 24 parallel to the inner face 22. Thus the stem 17 of the brush holder passes through the casing and the nut 19 engages with the face 24 of the boss and the outer end of the brush-holder engages with the inner face 22 of the casing so that the brush-holder is held in proper right angle relationship to the cam surface. Likewise, by reason of the casing being thickened by the boss 23, a firmer support is provided for the brush-holder.

This boss 23 furthermore acts to space the wire terminal 32, which is inserted between the nut 19 and binding nut 20, from the upset flange 31 which surrounds the opening in the timing gear case 30 in which the timer is mounted. In this manner all danger of

short circuit by the terminal striking this flange is eliminated. The outer end of the casing 18 is provided with a protuberance 25 having its center portion provided with a depression 26 within which a projection 27 on an arm 28 is adapted to engage for the purpose of holding this casing in position. This arm is the usual arm employed in the Ford cars. When the timer is used on the 10 Fordson tractor, then the member 29 (see Fig. 3), engages the outside periphery of the protuberance 25 and holds the casing in position. In other words, this protuberance is so formed that it is capable of use with either 15 the holding means employed in the Ford cars or the Fordson tractor. As the parts of this timer need no lubrication, and as any oil which accumulates in the casing would be detrimental to the operation of the timer, 20 I provide a drain hole 50 in the lower portion of the casing so that any oil will drain out of the casing. The arm 60 formed integrally with the cup-shaped insulating casing affords means for connection with the 25 lever whereby the insulating casing carrying the brushes may be rotated to advance or retard the spark.

While I have illustrated and described one embodiment of my invention, it will be understood that I do not wish to be limited to the exact construction shown and described, but that various changes and modifications may be made without departing from the spirit and intent of my invention.

35 What I claim as my invention is:

1. In a timing device, a rotary shaft having a reduced threaded end, this reduction in diameter of the shaft forming an annular shoulder, a metallic sleeve fitting on said 40 reduced portion of the shaft and having an interior longitudinal groove, a radial pin

on the reduced part of the shaft fitting in said groove, a clamp nut on the end of the reduced portion of the shaft abutting against the end of said sleeve and serving to jam it against said shoulder on the shaft, an insulating-sleeve surrounding said metallic sleeve, a metallic contact extending through said insulating-sleeve and into the metallic sleeve, this contact thereby serving to lock 50 the insulating-sleeve to the metallic sleeve, and a casing carrying a series of radial brushes bearing on the exterior surface of said insulating-sleeve.

2. In a timing device, a rotative contact, a 55 circular casing of insulating material open at one side and closed at the other side and having a plurality of brush-seats on the interior of said casing near its open side and a corresponding plurality of binding-nut-seats on the exterior of the casing, the casing at each pair of seats being thickened to provide a substantial support for the combined terminals and brush-holders, the faces of said brush-seats and binding-nut-seats being 60 flat, and the remaining portion of the inner wall of the rim of the casing being diverged toward the open side of the casing; a plurality of combined brush-holders and terminals each embodying a rigid member extending radially inwardly and having a flat outer end abutting one of the brush-seats, a spring-actuated brush carried by each one of these rigid radial members, a threaded shank carried by each one of these rigid 70 radial members and extending through a hole in the seats, a clamp-nut on each threaded shank, and a terminal-binding-nut on each threaded shank.

Signed by me at Chicago, Cook County, 75 Illinois, this 15 day of March, 1921.

ERNEST VON HAMBACH.
